UNITED STATES PATENT OFFICE.

HENRY WARD DARROW, OF WINAMAC, INDIANA, ASSIGNOR, BY MESNE ASSIGNMENTS, TO FRITZ MUSER, OF NEW YORK, N. Y.

REVERSIBLE DRIVING MECHANISM FOR CLOTHES-WRINGERS.

1,242,659.

Specification of Letters Patent.

Patented Oct. 9, 1917.

Original application filed December 7, 1908, Serial No. 466,337. Divided and this application filed September 8, 1916. Serial No. 119,029.

To all whom it may concern:

Be it known that I, HENRY WARD DARROW, a citizen of the United States, residing at Winamac, in the county of Pulaski and State of Indiana, have invented certain new and useful Improvements in Reversible Driving Mechanism for Clothes-Wringers, of which the following is a full, clear, and exact specification.

10 My invention relates to washing machines, more particularly to mechanisms for operating the rollers of clothes wringers, and consists in devising means, whereby the rollers of a clothes wringer, set in the usual 15 way upon a washing machine, may be operatively connected to the driving shaft of the washing machine, and a manually operatable controlling device whereby the roller driving mechanism is set in motion to rotate the wringer rollers forward or 20 reversely, irrespectively of the direction of rotation of the driving shaft of the washing machine, and may be stopped again without stopping or reversing the motor 25 driving the shaft of the washing machine.

A mechanism constructed according to my invention for thus operating a clothes wringer is shown and described in my application filed December 7th, 1908, Serial 30 Number 466,337, of which this application is a sub-division, in connection with the driving mechanism for a cylinder washing machine. The mechanism is shown in the accompanying drawings, wherein—

35 Figure 1 is an end elevation, and

Fig. 2 a side elevation of a washing machine with a clothes wringer set in position thereon, and having its rollers so operatively connected with the driving shaft 40 of the machine.

Fig. 3 is a fractional sectional view on line 3—3 indicated in Fig. 1, but drawn on an enlarged scale, of my improved mechanism for operating the rollers of the 45 wringer, and

Fig. 4 is a sectional view thereof on line 4—4 indicated in Fig. 3.

The washing machine shown in the drawings is no part of the invention claimed 50 herein, and is, therefore, shown and described herein only to the extent necessary for the understanding of the construction, and of the mode of operation, of the mechanism for operating the wringer, set up

thereon, by the motor and the driving shaft 55 of the washing machine.

The motor 35 is mounted on the base brace 28 of the washing machine frame, approximately midway between the posts 15. A pinion, fixed on the forward end of the 60 motor shaft, engages with the intermediate gear, by which the rotary motion of the motor shaft is transmitted to the shaft 49, the driving shaft of the washing machine. This shaft 49 extends from its terminal bearing 65 in block 47 (see Fig. 2) to the bushing 87 set adjustably in the casing 62, secured to the top of the washing machine frame, and wherein the mechanism for operating the wringer is arranged.

The wringer operating mechanism is shown in detail in Fig. 3 and comprises the beveled pinions 88 and 90 loosely set on the shaft 49, the intermediate shaft 94 journaled in the casing 62 at right angle to the shaft 49, and—in line with the shaft of the wringer gears,—clutch 95 being provided for coupling it thereto—the beveled pinion 96 fixed on the end of the shaft 94 and meshing with the pinions 88 and 90; 80 a flanged collar 117, splined to the shaft 49 by the key 118, and longitudinally movable thereon and the manually operatable controlling device, comprising the forked block 98, the crank 104, lever 107, and handle 108 for the shifting of the collar 117 on the shaft 49. The collar 117 rotates with the shaft 49 and is provided on both of its ends with recessed abutments for engaging with the correspondingly shaped projections 115 and 116 on the pinions 88 and 90, when shifted up or down from its normal, disengaged position shown in Fig. 3 of the drawing. The forked block 98 embraces the collar 117 between its annular flanges (see 95 Fig. 4) and its shank 100, extending into a longitudinal guideway 97 in the casing 62, is slotted. The crank 104 engages in the slot 99 of the shank; its one end is journaled in the casing 62 and its other end is fixed 100 in the eccentric bushing 101. The coil spring 105 and cap nuts 106 serve to hold the parts snugly together. The bushing 101 is connected, or made integral with, the lever 107, and a handle 108 is secured to 105 its free end for more conveniently moving the lever 107, whereby the crank 104 is turned. By so turning the crank 104, the

- collar 117 is moved in and out of engagement with either of the beveled pinions 88 and 90, thereby locking either of the pinions to the shaft 49, and causing it to rotate therewith. The beveled pinions 88 and 90 mesh, as above explained, with the pinion 96 fixed to the shaft 94, and when either of the pinions 88 or 90 is thus locked to the shaft 49, the shaft 94 is driven forward or reversely. By shifting the lever 107 into the position, shown in full lines in Fig. 2, the collar 117 is moved in engagement with the pinion 88 and the shaft 94 is set in motion rotating forward; by shifting lever 107 downward, in a position diametrically opposite to that shown in Fig. 2 in full lines, the collar 117 is shifted in engagement with the pinion 90 and the direction of the rotating motion of the shaft 94 is reversed. By setting the lever 107 in the position indicated in dotted lines in Fig. 2, the collar 117 is moved into its intermediate position, shown in Fig. 3, in which position it is not engaged with either of the pinions 88 and 90, and the gears and shaft 94 stand still.

A coupling 111 is provided on the outer end of shaft 94 for coupling thereto of the wringer driving shaft 110, whereby its rotation is transmitted to the rollers of the wringer 112. Thus by the moving of the lever 107, the rollers of the wringer are driven forward or reversely, as may be required. It is not necessary to stop or reverse the motor, driving the shaft 49 of the washing machine. The starting, reversing or stopping of the wringer rollers is effected and controlled independently of the motor and almost instantaneously, by merely moving, by hand, the lever 107 into its one or the other position, as explained above.

The employment of this mechanism for this almost instantaneously stopping or reversing the rotation of the wringer rollers is of great importance and advantage in the operation of power driven wringers, it being necessary, quite frequently, to reverse the direction of rotation of the rollers instantaneously, to prevent tearing of the clothes, when, as it quite often happens, some part of the garment gets caught on and winds around one roller, when a continuing rotation of the rollers in the forward direction would tear it. The power-driven wringers as heretofore constructed cannot be reversed, and thus the garment, if caught in the rollers, as it often happens and can hardly be avoided, is torn. In such a case also the wringer must be taken apart, to untangle the torn garment, which cannot be otherwise freed from the roller.

I claim as my invention:

1. The combination comprising a frame, a pair of rollers, rotatably mounted in the frame, intermeshing gears mounted on their

axes to convergently rotate the rollers, a driving shaft, gears mounted thereon, an intermediate shaft, operatively connected with the gears mounted on the axes of the rollers, a gear on the intermediate shaft meshing with the gears on the driving shaft, and manually operable means, controlling the operative connection of the gear on the driving shaft with the gear on the intermediate shaft; substantially as herein shown and described.

2. The combination comprising a frame, a pair of rollers, rotatably mounted in the frame, intermeshing gears fixed to the axes of the rollers, a driving shaft, gears loosely mounted thereon; an intermediate shaft operatively connected with the gears fixed to the axes of the rollers; a gear fixed on the intermediate shaft and meshing with the gears on the driving shaft; manually operable device for clutching either one of the gears to the driving shaft, and means for rotating the driving shaft; substantially as herein shown and described.

3. The combination comprising a frame, a pair of rollers, rotatably mounted in the frame, intermeshing gears, fixed on their axes, for convergently rotating the rollers, a motor, a driving shaft operatively connected therewith; two bevel gears loosely mounted on the driving shaft; a collar slideable on the driving shaft between the bevel gears and rotating with the shaft, coupling means on each end of the collar, and on the gears; manually operable means for shifting the collar in engagement with one of the gears; an intermediate shaft, a gear fixed thereto meshing with the gears on the driving shaft, and means operatively connecting the intermediate shaft with the gears fixed on the axes of the rollers; substantially as herein shown and described.

4. The combination comprising a frame, a pair of rollers, rotatably mounted in the frame, intermeshing gears, fixed on their axes, for convergently rotating the rollers, a motor, a driving shaft operatively connected therewith; two bevel gears loosely mounted on the driving shaft; an intermediate shaft, and means operatively connecting it with the gears fixed to the axes of the rollers; a bevel gear fixed on the intermediate shaft, meshing with the two gears on the driving shaft, and manually operable means for locking either of the two gears to the driving shaft; substantially as herein shown and described.

5. The combination comprising a frame, a pair of rollers, rotatably mounted in the frame, intermeshing gears, fixed to the axes of the rollers, a motor, and a driving shaft operatively connected therewith; selective gears, loosely mounted on the driving shaft; a shaft, operatively connected with the gears fixed to the axes of the rollers, and with

the selective gears on the driving shaft, and manually operable means for locking either one of the selective gears to the driving shaft; substantially as herein shown 5 and described.

6. The combination comprising a frame, a pair of rollers, rotatably mounted in the frame, gears, fixed to the axes of the rollers; a motor, and a driving shaft operatively 10 connected therewith; gears mounted on the driving shaft; an intermediate shaft, operatively connected with the gears fixed on the

axes of the rollers; a gear on the intermediate shaft, meshing with the gears on the driving shaft, and manually operable 15 means controlling the operative connection of the gears on the driving shaft with the gear on the intermediate shaft; substantially as herein shown and described.
